CLAIM

The ornamental design for the “paint cap closure with folding and latching exterior handle,” as shown and described.

DESCRIPTION

FIG. 1 is a front perspective view of the paint cap closure with folding and latching exterior handle.

FIG. 2 is a view of the paint cap closure assembled in a typical pail lid showing a line X—X that does not form part of the design.

FIG. 3 is a perspective view of the paint cap closure in an alternate configuration with its handle not folded in and not latched.

FIG. 4 is a side view of the paint cap in an alternative configuration with its exterior handle partially folded and not latched.

FIG. 5 is a side view of the paint cap closure assembled in a typical pail lid with partial cross-sectional view along the line 5—5 previously illustrated in FIG. 2, wherein its exterior handle is folded in and its pull ring is engaged with its interior latch.

FIG. 6 is a top view of the paint cap closure; and,

FIG. 7 is a bottom view of the paint cap closure.

The broken lines in the drawings depict environmental subject matter only and form no part of the claimed design.
